(57) **CLAIM**

The ornamental design for a clamp for rod rotator, as shown and described.

DESCRIPTION

FIG. 1 is a left side view of the clamp.

FIG. 2 is a right side view of the clamp.

FIG. 3 is a front view of the clamp.

FIG. 4 is a back view of the clamp.

FIG. 5 is a top view of the clamp.

FIG. 6 is a bottom view of the clamp.
FIG. 7 is a perspective view of the clamp; and,
FIG. 8 is another perspective view of the clamp.
